George F. Shewell, Baltimore, Md., assignor to
Hedwin Corporation, Baltimore, Md., a corpora-
tion of Maryland

Application July 3, 1951, Serial No. 15,750

Term of patent 14 years

(Cl. D92—26)

To all whom it may concern:

Be it known that I, George F. Shewell, a citizen of the United States, residing at Baltimore, Maryland, have invented a new, original, and ornamental Design for an Embossed Plastic Table Mat, of which the following is a specification, reference being had to the accompanying drawing, forming part thereof.

Figure 1 is a top view of an embossed plastic table mat, showing my new design; and

Figure 2 is a cross-section of the embossed plastic table mat and is taken along the line 2—2 of Figure 1.

I claim:

The ornamental design for an embossed plastic table mat, as shown.

GEORGE F. SHEWELL.
